(57) **CLAIM**

The ornamental design for a “game paddle” as shown and described.

DESCRIPTION

FIG. 1 is a front view of a game paddle in accordance with the present disclosure;

FIG. 2 is a rear view of the game paddle of FIG. 1;

FIG. 3 is a right side view of the game paddle of FIG. 1;

FIG. 4 is a left side view of the game paddle of FIG. 1;

FIG. 5 is a bottom view of the game paddle of FIG. 1;

FIG. 6 is a top view of the game paddle of FIG. 1;

FIG. 7 is a first perspective view of the game paddle of FIG. 1; and,

FIG. 8 is a second perspective view of the game paddle of FIG. 1.

The broken lines show portions of the game paddle and form no part of the claimed design.

1 Claim, 5 Drawing Sheets
